CARRIER BAR CONTROL MECHANISM

Joseph L. Beers, Bloomfield, N. J., assignor to
Julius Kayser & Co., New York, N. Y.

Application April 13, 1940, Serial No. 329,425

18 Claims. (Cl. 66—130)

The invention generally relates to a flat knitting machine, and has for its principal object the selective operation of one or more carrier bars in a predetermined sequence, and the snubbing and locking of the carrier bars as they approach and reach their final limit of travel in completing their yarn laying operation.

The invention more particularly pertains to a full-fashioned hosiery knitting machine, and has to do with the combination of a yarn carrier bar selecting mechanism and a novel type of snubbing and locking device operating in synchronism with the selecting mechanism to automatically snub the final movement of the carrier bars and lock the same.

Specifically the present invention contemplates the provision of a mechanism automatically functioning to control in selective fashion a plurality of yarn carrier bars of a flat knitting machine, this application being a continuation in part of my copending applications Serial Number 696,473, filed November 3, 1933, and Serial Number 266,657, filed June 14, 1935, which applications under date of September 9, 1940, matured into Letters Patents No. 2,213,298 and No. 2,213,299, respectively.

It is the primary purpose of the invention to provide a mechanism operatively associated with a carrier bar of a flat knitting machine, and operable to brake the travel of said bar as it approaches the limit of its stroke, said mechanism also being adaptable to lock the carrier bar upon reaching the end of its stroke.

The invention particularly aims to provide, in a full-fashioned knitting machine, a locking device capable of producing a braking action for the snubbing of the final movement of each of a plurality of carrier bars into stopped position, and locking the same against rebound, said device being operated directly from a working part of said machine.

It is also an important object of the invention to provide a locking device which is mounted independently of the narrowing head and is not subject to the rebounds of the vibratory actions of the narrowing head, thereby eliminating the possibility of broken needles, sharpened sinkers, cut-ins, and poor selvedges.

Another object of the invention resides in the provision of a locking device having a plurality of carrier bar engaging elements, one for each of a plurality of carrier bars in a flat knitting machine, each element being in permanent engagement with its corresponding carrier bar and op-

eratively associated with means to govern its function in a positive, assured manner.

The invention moreover contemplates the incorporation, in a unitary mechanism, of a carrier bar locking and releasing device and a carrier bar operating device, said devices being operated and controlled directly from the friction rod and main cam shaft of the knitting machine.

A feature of the invention also resides in the direct association and connection of the locking device with the drive mechanism for the carrier bars, whereby the two devices are operated in unison and in proper timed relation to prevent improper operation and locking of the carrier bars.

Another feature of the invention resides in the direct relation between a brake and driving mechanism, and of the friction rod and friction box associated therewith, whereby the frictional action of the brake is applied before the frictional pressure of the carrier bar against the narrowing head stop is released, thereby firmly and frictionally holding the carrier bar in position to prevent rebound.

The invention is moreover distinguished by the novel features and method of operation of the braking device and the mechanism for setting into operation said braking device, and also the carrier bar operating device which may be associated therewith.

With these and other objects in view, the invention will be better understood from the following detailed description, taken in conjunction with the accompanying drawings, wherein:

Figure 1 is an elevation of the braking and locking device showing its association with parts of the knitting machine.

Figure 2 is a detail of a portion of the mechanism shown in Figure 1.

Figure 3 is a detail in cross section of one of the brake devices.

Figure 4 is a detail of the operating ratchet elements.

Figures 5, 6, and 7 diagrammatically illustrate the respective positions of the actuating cams.

Figure 8 is an enlarged view showing the combination of the brake device and carrier bar driving device.

Figure 9 is a detail on a reduced scale of a portion of the mechanism shown in Figure 8.

Figure 10 is a plan of the combined brake device and carrier bar driving device.

Figure 11 is a rear elevation of the same.

Figures 12 to 16 inclusive diagrammatically

show the successive steps in the operation of the device.

Figure 17 is a section illustrating a modified construction of the invention.

The mechanism shown in the drawings is equipped for association with three carrier bars, although it is to be understood that the mechanism may be readily constructed for association with a different number of carrier bars.

The mechanism is operated from the main cam shaft 10 of the machine by a cam 11 engaging a roller 12 on an arm 13 pivoted at 14 on a bracket 15 mounted on a portion 16 of the usual frame of the knitting machine. The roller 12 is moved away from the shaft 10 by the action of the cam 11 and the return movement is effected by means of a spring 17 connected to the arm 13 and anchored to a suitable part of the machine frame. A shogging movement of the main cam shaft 10 brings a member or idle cam 18 into engagement with the roller 12 so that the mechanism remains inactive until such time as the shaft 10 is again shogged to bring the cam 11 back into engagement with the roller 12.

Secured to the arm 13 is a second arm 19 which is connected to a rod 20 for operating an arm 21 pivotally mounted on one of the shafts (such as the fashioning shaft 22) at the rear of the knitting machine. The arm 21 carries a pawl 23 adapted for engagement with the teeth of a ratchet wheel 24 secured to a cam sleeve 26 mounted on said shaft 22.

The carrier rod braking and locking device is mounted above, and is controlled by, said cam sleeve 26 in the manner hereinafter described. A supporting bar 28 is suitably mounted on fixed portions of the framework of the knitting machine and carries a bracket 29 secured thereto by means of screws 30, or like fastening elements.

Mounted in ball-bearings 41 so as to rotate freely in the bracket 29 are shafts 42 having their end portions extended to project outwardly of said bracket carried on a bar 28. Mounted upon one end of each shaft 42 is a gear 43 which meshes with, and actuates, a toothed rack 44, the latter being provided with depending lugs 45 to which is secured one of the usual carrier rods 46 supporting the thread carrier fingers 47 of any suitable well known type.

The carrier rods 46 are supported and guided on the machine in the usual well known manner, and the thread carrier fingers 47 are arranged at suitable positions so as to lay the thread in any desired manner. The carrier rods 46 are adapted to receive their yarn laying movements in the customary manner through actuation of the usual friction rod 48 and main friction boxes, one of which is shown at 49 in Figure 11 of the drawings. Each friction box 49 is preferably provided with pivot fingers 50 adapted to be swung into, or out of, operative engagement with the respective carrier bars.

Mounted upon the other end of each shaft 42 is an externally grooved brake pulley 51 and associated with each pulley is a brake 52 adapted to snub the rotation of the associated pulley when the carrier bar approaches the limit of its stroke, and to stop the rotation of said pulley and lock the same when the carrier bar has reached its final distance of travel and has contacted its respective end stop.

As clearly shown in Figure 3, each brake device consists of a pair of centrally pivoted jaws 53 and 54 mounted in the groove of the pulley. These jaws are adapted to be swung into fric-

tional engagement with the walls of the groove of the pulley when moved about their pivots 55. To swing the jaws about their pivots, there is preferably provided a wedge shoe 56 having one end pivoted to one of the jaws, as indicated at 57, and its other end shaped into a cam 58 disposed to bear upon a roller 59 carried by the other jaw. This shoe 56 is drawn into braking position by means of a spring 60 having one end connected to the shoe and its other end connected to a stationary part of the attachment. The shoe is moved against the action of the spring 60 by means of a lever 61 mounted on a stub shaft 62 carried by bearing brackets 63 on the bar 28, said lever having an extension 64 carrying an adjustable stop 65 disposed to bear directly against a set screw 66 carried by the shoe 56. Thus it will be appreciated that when movement is given to the lever 61, the extension 64 will control the action of the shoe 56, that is to say, when the lever swings in the direction indicated by arrow A, the extension 64 will depress the shoe 56 against the action of the spring 60 thus destroying the braking action by allowing the jaws 53 and 54 to move out of frictional engagement with the walls of the groove in the pulley 51, but when the lever swings in the direction of arrow B, the extension 64 will recede from the shoe 56, allowing the spring 60 to move said shoe in wedging engagement with the roller 59 thus causing the jaws 53 and 54 to move into frictional engagement with the walls of the groove in the pulley 51.

Swinging movement is imparted to the lever 61 by means of the cam sleeve 26 which, for that purpose, is actuated with a step-by-step motion in proper timed relation to the operation of the machine, and carries three sets of cams 68 co-operating with rollers 69 on the levers 61 to swing the same successively. The sets of cams 68 are spaced at substantially 90° apart, as clearly shown in Figures 5, 6, and 7, enabling one lever at a time to be moved into position to release the braking jaws 53 and 54, thereby freeing the carrier bars one at a time, and to snub or brake the movement of said carrier bars as they approach the end of their travel in the manner to be described fully hereinafter.

As hereinbefore stated, the invention also contemplates the association of a carrier bar operating device with the carrier bar locking and releasing device just described. This is preferably accomplished, as shown in Figures 8 to 11, inclusive, by mounting on the bar 28 between the bracket 29 and the guide member 70 a longitudinally movable toothed rack 71 adapted to be automatically reciprocated in timed relation to the operation of the machine through the medium of the friction rod 48 and main friction box 49. For that purpose, the main friction box 49 carries a member 72 having a projecting end 73 disposed to engage a recess in one face of said rack 71, the rack being held in engagement with the member by means of a set screw 74. In this manner, the movement of the friction rod 48 is transmitted to the rack 71 which, in turn, actuates three toothed pinions 75 for the actuation of the three thread carrier bars 46 embodied in this improved attachment.

Each of the three pinions 75 is fixedly mounted upon a sleeve 76 loose on the shaft 42, and is connected by pins 77 to one member 78 of a clutch, the cooperating member 79 of which is mounted upon said sleeve 76 so as to rotate freely

thereon and so as to move axially and out of clutching engagement with the member 78.

Secured to each clutch member 79 and extending through the adjacent brake pulley 51 are guide pins 80 adapted to slide freely through said pulley as the clutch is engaged or disengaged.

Secured by means of nuts 81 to the free ends of the pins 80 is a disc 82, while a coil spring 83 is held in compression between said disc 82 and pulley 51 so that the clutch member 79 is normally held out of engagement with its co-operating member 78.

The operation of the clutch members 78 and 79 is effected by means of an extension 84 on the lever 61. This extension 84 is provided with an adjustable tappet 85 adapted to bear against the disc 82 so that the clutch member 79 may be moved towards the clutch member 78 for the interconnection thereof and the driving of the shaft 42. The arrangement is such that the actuation of the rack 71 from the friction box 43 rotates all the pinions 75, but the clutch members are so actuated that only one of the pinions 75 imparts its rotary motion to the corresponding gear 43 so that one of the racks 44 is actuated in synchronism with the rack 71 while the remaining racks 44 remain stationary.

Attention is called to the fact that a single lever 61 and one set of cam members 68 control the operation of both a brake device and a clutch, and through the latter, the selective operation of a gear 43.

The tappet 85 consists of a spring pressed plunger 86 having a limited movement relative to the barrel 87 in which it is mounted, which barrel is formed in said extension 84 of the lever 61. The plunger 86 is adapted to come into direct contact with the disc 82 when the lever has been thrown the required distance to bring about engagement of the clutch members. Each plunger is provided with a lug 68 arranged in the path of movement of a centrally pivoted control finger 89 mounted directly upon the lever and moved therewith, but capable of swinging independently thereof.

The improved control includes the stub shaft 62 upon which all the levers 61 are loosely mounted and, further, comprises a plurality of manipulators 90 fixed to the shaft 62 to move therewith. These manipulators 90 include pins 91, certain of which are operatively associated with the fingers 89 and certain others of which are adapted to engage abutments 92 projecting from the lever extensions 84 so that the lever 61, fingers 89, and pins 91 may be set properly in their relative positions for the release of all of the clutches.

The shaft 62 is manipulated by means of a lever 93 having suitable detent locking mechanism such, for instance, as disclosed in the co-pending application, Serial Number 26,657, aforesaid, whereby the shaft 62 may be rocked to, and locked in, either of two positions.

When the shaft 62 is turned by the lever 93, certain of the pins 91 are engaged with the fingers 89 for retracting their associated plungers and, further turning movement of the shaft 62 by the lever brings the remaining pins into engagement with the abutments 92 for rocking all of the levers 61 in position out of engagement with the sets of cams 68. The throwing of the levers 61 by the control is limited by stop pins 95 carried by the levers and adapted to engage a stop member 96 on the supporting bar 28. In view of the fact that one plunger 86 is always in

engagement with its plate 82 due to the circumferential arrangement of the cam members 68, it will be understood that this particular plunger must be retracted the required distance to render the then active gear 43 inactive. This is accomplished after all the levers have been moved into proper alignment with each other and the respective plungers 86 retracted by the swinging of all the control fingers 89.

If advisable in practice, an indicator 97 may be used, and this indicator is mounted on the shaft 62 and turns thereabout. An extension 98 thereon comes into contact with the cam 68 as indicated in Figure 11 of the drawings. With the use of the control, the entire attachment may be readily rendered inoperative thereby enabling the usual friction on a full-fashioned knitting machine to be put into operation for the actuation of the thread carrier bars.

In the operation of the carrier bars, the knitting machine is set in motion, and in the control of the shaft 22 by the ratchet mechanism driven off the main cam shaft 10, the sleeve 26 is turned, and with it the sets of cam members 68. As these sets of cam members are moved in their respective circular path, they swing the levers 61 one at a time, and in the swinging of the levers 61, the individual clutch members are thrown into locked position for operating the respective shafts 42, thereby rotating gears 43 for the operation of the carrier bars, and simultaneously with the rotation of each gear 43, the remaining gears are held against rotation by the application of their associated brake devices.

By adjusting the stops 65 on extension 64 and the set screw 66 on the brake shoe 56 in relation to the tappet 85 on the extension 84, the relative operation of the brake and clutch may be timed so that the brake is gradually released as the clutch is engaged, and conversely the brake is gradually applied as the clutch is moved to disengaging position. In this manner, it is possible to check and brake the movement of the carrier bar as it approaches the limit of its stroke.

The successive steps in the operation of the brake and clutch mechanism will be better understood with reference to Figures 12 to 16 inclusive. In Figure 12, the lever 61 is shown in its neutral position. In this position, the cam 68 being out of contact with the roller 69 of the lever 61, the clutch is fully disengaged while the brake is fully engaged, thus locking the carrier bar against movement in the manner hereinbefore stated. As the cam 68 is rotated in the direction of arrow C, the inclined face *a* of said cam is brought in contact with the roller 69. As shown in Figure 13, the continued movement of the cam 68 in the direction of arrow C causes said inclined face *a* of the cam to gradually swing the lever 61 in the direction of arrow A, displacing the extension 64 in the direction of arrow E, thus forcing the brake shoe 56 in the direction of arrow E' for gradually releasing the brake as the clutch is being moved into engaging position until the high face *b* of the cam contacts the roller 69, as shown in Figure 14, when the brake is fully released and the clutch is fully engaged.

As illustrated in Figure 15, when the cam 68 is again moved in the direction of arrow C, the roller 69 rides down the inclined face *c* of said cam whereby the lever 61 is gradually swung in the direction of arrow E, thus displacing the extension 64 in the direction of arrow F, and permitting the brake shoe 56 to move in the direc-

tion of arrow F', accordingly causing the brake to be applied.

While the movement of the lever 61 in the direction of arrow B will also cause the extension 84 to move in the direction of arrow G, tending to permit the clutch to move towards disengaging position, the adjustment of the tappet 85 in relation to the elements 65 and 66 of the brake mechanism is such that the clutch does not become fully disengaged until the cam 68 has left the roller 69, as shown in Figure 16, so that, although the brake is applied as above set forth when said cam 68 starts to recede from the roller 69, the clutch remains sufficiently engaged to continue the driving of the carrier bar to the end of its stroke. Therefore, it will be understood that the carrier bar actually is checked in its yarn laying movement as it approaches the limit of its stroke.

In order that the brake may be applied before the cessation of the carrier rod movement when knitting both in the wide and narrow portions of the fabric, the angle and length of the inclined cam face is so calculated, and the adjustments of the elements 65, 66, and 85 are so regulated, that the brake is actuated to start its braking action at a point during the movement of the carrier bar in advance of the end of its narrowest stroke. The fact that said adjustments might cause the clutch to remain in engagement, although the carrier is arrested while the friction bar 48 continues to the end of its stroke, has no detrimental effect, since the rack 71, as best shown in Figure 11, is driven through the friction box 49, which will slip, as usual, whenever resistance occurs.

In view of the foregoing, it will be appreciated that as each carrier bar reaches its position of rest, the frictional action of the friction rod forces the carrier bar against the end stop, and before the carrier bar is relieved of its frictional pressure, a brake device has been set into operation for gradually braking and finally locking the carrier bar against rebound. This is a very important feature of the invention, because it enables the proper timing of the locking of the bar with its final movement under frictional pressure. When the carrier bar has been brought to rest and relieved of the turning action of its associated pinion due to the swing of the plunger 86 away from the plate 82, and the extension 64 has swung away from the shoe 56, thereby enabling the spring 60 to retract and draw the shoe into braking engagement with the jaws of the braking device, the jaws then grip the pulley tightly and lock the carrier bar securely against its stop, due to the fact that the pinion is prevented from turning because of the engagement of the brake with the pulley.

Through the use of the control device hereinbefore described, it is possible to render the entire mechanism inoperative insofar as the operation of the carrier bars is concerned, thereby enabling the carrier bars to be operated in the usual manner.

With reference to the use of the braking device alone, that is, the use of a braking device without the driving device as is shown more clearly in Figure 1, it will be appreciated that the operation of said braking device for snubbing or braking the movement of the carrier bar as it approaches the limit of its stroke is the same as described in conjunction with the combined braking and driving devices. In other words, the brake actuating elements represented in Figure 1 are relatively adjusted so that the braking action on the carrier

bar which, in this instance, is driven by the ordinary friction drive, occurs before the carrier bar reaches the end of its reciprocating movement as, and for the purpose, hereinbefore explained.

5 In Figure 17 of the drawings, there is shown a modified construction of the clutch and brake actuating mechanisms. In this construction, the operation of the clutch is effected by means of a lever 61a pivotally mounted on the stub shaft 10 in bearing bracket 63, the upper end portion 10 or extension 84a of the lever 61a being provided with an adjustable screw pin 86a adapted to engage a cushioning spring 100 mounted into clutch engaging disc 82. The lower end of the lever 61a 15 carries a roller 69a for engagement with a clutch operating cam 68a on the shaft 22.

The brake pulley 51 cooperates with a brake device comprising an arcuate brake shoe 101 and a friction member 102 for engagement with the groove of said pulley. The brake shoe 101 is carried upon a plunger 103 mounted in a sleeve 104 adapted to slide vertically in a bracket 105 on the supporting bar 28. The lower extremity of the sleeve 104 carries a roller 106 for engagement with a brake actuating cam 68b. The brake device is normally pressed downwardly by means of a spring 107 in compression between said bracket 105 and a shoulder 108 on the sleeve 104. An internal spring 109 is interposed between the bottom of the socket in the sleeve 104 and the lower extremity of the plunger 103 so as to provide a cushioning effect in the braking action, and a pin 110 on the plunger 103 traverses registering slots (not shown) in the sleeve 104 and bracket 105 so as to limit the relative movement between said parts.

40 In the use of this modified construction, the operation of the clutch and brake is substantially the same as that of the preferred construction in that the relative positions of the cams 68a and 68b and the adjustments of the screw pin 86a are such that the brake operates to snub or brake the movement of the carrier bars as they approach the end of their stroke and to lock said carrier bars when they reach the end of their movement, the essential difference between the two constructions being that in the preferred form, the clutch and brake actuating mechanisms are combined and but a single set of cams 68 is required to actuate said mechanisms, whereas in the modified form, the clutch and brake actuating mechanisms are separate and two sets of cams are required, one set 68a controlling the clutch, and the other set 68b controlling the brake.

45 Of course, it will be understood that, as in the preferred form, the brake mechanism of the modified form may be used without the clutch mechanism. In that case, the carrier bars will be driven by the usual friction, the brake operating to snub and lock the carrier bars in the manner hereinbefore specified.

50 It is also to be understood that the various possible embodiments herein shown and described are capable of certain modifications without departing from the gist of the invention. Therefore, any modifications coming within the scope of the subjoined claims are to be considered within the spirit of the invention.

55 In concluding, it is pointed out that my control mechanism is particularly advantageous in the selecting, driving, braking, and locking of carrier bars in their function in the knitting of flat fabric in accordance with the so-called

Three-Carrier System, wherein three carrier bars are used, two located at one end of the machine and one located at the other end of the machine. With such an arrangement, it will be understood that my control mechanism is readily adaptable for the selective automatic unlocking and driving of the carrier bars one at a time in repeated sequence, and the braking and locking of each bar as it reaches its final limit of travel in either direction.

What I claim is:

1. In a flat knitting machine, the combination with a reciprocating carrier bar, of a mechanism including means in permanent positive engagement with the carrier bar and operable to brake the travel thereof as it approaches the limit of its stroke and to lock said carrier bar upon reaching the end of its stroke.

2. In a flat knitting machine, the combination with a reciprocating carrier bar, of a mechanism including means in permanent positive engagement with the carrier bar and operable to brake the travel thereof as it approaches the limit of its stroke, and to lock said carrier bar upon reaching the end of its stroke in either direction.

3. In a flat knitting machine, the combination of a carrier bar and means functioning for imparting reciprocating movements to the carrier bar, of a device including means in permanent positive engagement with the carrier bar and operable to first snub and brake the movements of the carrier bar at certain times during the function of said movement imparting means, and thereafter lock the carrier bar against movements.

4. A locking device for carrier bars comprising means in permanent positive engagement with the carrier bars for selectively snubbing and locking the latter and selecting mechanism controlling the selection of said means.

5. A locking device for carrier bars comprising means in permanent positive engagement with the carrier bars for selectively snubbing and locking the latter, and a progressively operable mechanism for controlling the selection of said means.

6. In a flat knitting machine, in combination with a set of carrier bars and a power device of the knitting machine, arresting and locking mechanism for said carrier bars for selectively arresting and locking the carrier bars in the operation thereof, said mechanism comprising a brake pulley for each carrier bar having an operative connection therewith; a device coacting with each pulley for controlling the movement thereof; an actuating cam associated with each device; and operative connections between all of said actuating cams and the power device of the knitting machine whereby said cams may selectively operate said devices for selectively controlling the movement of the brake pulleys.

7. In a flat knitting machine, the combination with a plurality of carrier bars, and a mechanism for selectively operating said carrier bars in predetermined sequence, of means incorporated into and acting in synchronism with said mechanism for selectively braking the travel of a carrier bar as it approaches its limit of travel in either direction, and holding said carrier bar in its final position of rest.

8. In a full-fashioned knitting machine, in combination with at least three carrier bars, two located at one end of the machine and one located at the other end of the machine and each reciprocating in repeated sequence from one end

to the other end of the machine, of a single mechanism for the selective automatic unlocking of the carrier bars one at a time in repeated sequence for reciprocation in either direction, and braking and locking each bar as it reaches its final limit of travel in either direction.

9. In a flat knitting machine, the combination with a carrier bar driven for reciprocating movement, of a carrier bar snubbing and locking device comprising: a rotary member supported for axial rotation in the longitudinal plane of the carrier bar and having positive engagement therewith to normally be rotated thereby; and frictional means operable to engage the rotary member frictionally for braking the rotation thereof whereby to brake the reciprocating movement of the carrier bar in positive engagement therewith.

10. In a flat knitting machine, the combination with a plurality of carrier bars each driven for individual reciprocating movement, of a carrier bar snubbing and locking device comprising: a rotary member for each carrier bar supported for axial rotation in the longitudinal plane of the latter and having positive engagement therewith to normally be rotated thereby; and friction devices, one for each rotary member, and operable to engage the latter frictionally for braking the rotation thereof, whereby to brake the reciprocating movement of the carrier bar in positive engagement therewith.

11. In a flat knitting machine, the combination with a carrier bar driven for reciprocating movement, of a carrier bar snubbing and locking device comprising: a toothed rack fixed on the carrier bar longitudinally thereof for reciprocation therewith; a gear device rotatably supported transversely of the carrier bar and enmeshed with the toothed rack thereon to normally be rotated by the reciprocation thereof; and means operable to engage said gear device for braking the rotation thereof whereby to brake the reciprocating movement of the carrier bar through said rack.

12. In a flat knitting machine, the combination with a plurality of carrier bars, each driven for individual reciprocating movement, of a carrier bar snubbing and locking device comprising: a toothed rack fixed on each carrier bar longitudinally thereof for reciprocation therewith; a gear device for each carrier bar rotatably supported transversely thereof and enmeshed with the toothed rack thereon to normally be rotated by the reciprocation thereof; friction devices, one for each gear device, and operable to engage the latter for braking the rotation thereof whereby to brake the reciprocating movement of the carrier bar through the rack fixed thereon and enmeshed with said gear; and a mechanism for operating said friction devices in synchronism with the individual reciprocating movement of each carrier bar.

13. In a flat knitting machine, in combination with a plurality of reciprocating carrier bars, arresting and locking mechanism therefor, comprising: a control device for each carrier bar and operable first to brake the movement of the associated carrier bar when approaching the end of its stroke in either direction, and then to lock the same upon reaching the end of its stroke in either direction; and, means common to all of said devices for selectively operating each device to arrest and lock its associated carrier bar.

14. In a flat knitting machine, in combination with a plurality of reciprocating carrier bars and

a main cam shaft, arresting and locking mechanism for said bars comprising: a control device for each carrier bar and operable first to brake the movement of the associated carrier bar when approaching the end of its stroke in either direction, and then to lock the same upon reaching the end of its stroke in either direction; and, means common to all of said devices for selectively operating each device to arrest and lock its associated carrier bar, said means including actuating elements, one for each of said control devices, and connections between the main cam shaft and said elements for selectively actuating the latter.

15. In a flat knitting machine, the combination with a carrier bar driven for reciprocating movement, of a carrier bar snubbing and locking device comprising: a rotary member supported for engagement with the carrier bar to normally be rotated thereby; and means operable to engage the rotary member for braking the rotation thereof, whereby to brake the reciprocating movement of the carrier bar in engagement therewith.

16. In a flat knitting machine, the combination with a plurality of carrier bars, each driven for individual reciprocating movement, of a carrier bar snubbing and locking device comprising: a rotary member for each carrier bar supported for engagement therewith to normally be rotated thereby; and, devices, one for each rotary member, and operable to engage the latter for braking the rotation thereof whereby to

5 brake the reciprocating movement of the carrier bar in engagement therewith.

17. In a flat knitting machine, the combination with a carrier bar driven for reciprocating movement, of a carrier bar snubbing and locking device comprising: a toothed rack on the carrier bar and reciprocating therewith; a gear device rotatably supported for engagement with the toothed rack on the carrier bar to normally be rotated by the reciprocation thereof; and, means operable to engage said gear device for braking the rotation thereof whereby to brake the reciprocating movement of the carrier bar through said rack.

18. In a flat knitting machine, the combination with a plurality of carrier bars each driven for individual reciprocating movement, of a carrier bar snubbing and locking device comprising: a toothed rack on each carrier bar and reciprocating therewith; a gear device for each carrier bar rotatably supported for engagement with the toothed rack thereon to normally be rotated by the reciprocation thereof; devices, one for each gear device and operable to engage the latter for braking the rotation thereof whereby to brake the reciprocating movement of the carrier bar through the rack thereon and in engagement with said gear; and, a mechanism for operating said devices in synchronism with the individual reciprocating movement of each carrier bar.
